UNITED STATES PATENT OFFICE

GUY A. ROBINSON, OF CINCINNATI, OHIO

GAS RANGE

Application filed July 24, 1929. Serial No. 380,622.

This invention relates to improvements in means for regulating the heating efficiency of gas ranges.

It is well known to users of natural gas that during periods of large consumption the heating efficiency of gas ranges is very often inadequate. It is caused by a diminution of pressure by reason of large consumption, so that the tip of the flame is too far below the utensil being heated. It is also known that there are considerable fluctuations in gas pressure in various parts of the country. Furthermore, the conventional gas range, utilizing manufactured gas, and even ordinary natural gas, is not suitable for use with liquefied natural gas, because the utensil supporting grid of the conventional range is too far spaced from the burner. For these reasons, the present invention includes a gas range comprising an upstanding frame wall structure, upon which the top wall is adjustably mounted by improved means; the top wall structure supporting a plurality of grids which are elevated and lowered with the top wall frame structure in a variable relation with respect to stationary burners, so that the proper spacing of burners with respect to the plurality of grids may be obtained, best suited to the type and character of gas being used.

Other objects and advantages of this invention will be apparent during the course of the following detailed description.

In the drawings, wherein similar reference characters designate corresponding parts throughout the several views,

Figure 1 is a fragmentary plan view, partly in section, showing a gas range structure, with the improved top wall and grid elevating and lowering mechanism.

Figures 2 and 3 are cross sectional views taken substantially on the line X—X of Figure 1; Figure 2 showing the top plate elevated and spaced a considerable distance from the burners, and Figure 3 showing the top plate

lowered to closely space the grids with respect to the burner.

Figure 4 is a sectional view taken substantially on the line 4—4 of Figure 1.

Figure 5 is a horizontal sectional view, 50 showing in dotted lines the plan view of a range with a modified type of top wall and grid elevating and lowering means.

Figures 6 and 7 are sectional views taken substantially on the line Y—Y of Figure 5; 55 the section of Figure 6 showing the top wall of the range of Figure 5 spaced with its grids a considerable distance from the burners; the sectional view of Figure 7 showing the top wall and grid closer to the burner. 60

Figure 8 is a sectional view taken on the line 8—8 of Figure 5.

In the drawings, wherein for the purpose of illustration are shown preferred and modified forms of the invention, the letter A may 65 generally designate the preferred form of invention, shown in Figures 1 to 4 inclusive, and B may generally designate the modified form of invention shown in Figures 5 to 8 inclusive. 70

In both forms of invention it is preferred to provide a range or stove including a main frame comprising upstanding opposed side walls 11 and 12 connected by transverse walls or braces 13 and supported by legs or any other approved structure. The walls 11 and 12 and brace means 13 may support a plurality of burners 14, 15, 16 and 17, in any approved conventional manner; the same being detachable upon the stationary frame 80 of the range, and respectively having conduits leading to their gas regulating valve structures 19, 20, 21 and 22. A suitable drip pan 23 may be removably carried by the walls 11 and 12 and the means 13, below the stationary burners 14 to 17 inclusive, for well known reasons. 85

Furthermore, in both forms of invention, the ranges include a top wall structure C, which includes the preferably solid marginal 90

portion 16^a, having the laterally extending flange portions 17^a, and being provided with openings therein above each of the burners 14 to 17 inclusive, for respectively supporting 5 detachable grids 24 thereover. The grids 24 are polygonal in form, although they may be of any other shape, and of course, the top wall C is suitably provided with cross beams 25, of well known construction connected 10 with the marginal portions 16^a of the top wall, and formed to detachably receive the grids 24 thereon. It is of course understood that a detachable grid is provided for each burner, so that in the example shown there 15 are four burners and four individual grids therefor.

Referring to the form of invention A, the entire top wall structure C including the grids 24 thereof is bodily movable into a desired adjustable spaced relation with respect to the burners. The arrangement is shown in Figures 1, 2, 3 and 4, and includes a pair of rotatable shafts 30 and 31, secured by end and intermediate brackets 32 in a 20 horizontal rotatable relation at the insides of the opposite range stationary frame walls 11 and 12 respectively, as shown in Figure 1 of the drawings. The shafts 30 and 31 are provided with end pinions 35 and 36 respectively, housed within the end brackets 32; the latter being hollow and over-roofing the pinions 35 and 36 as a protection therefor, as shown in Figures 2 and 3 of the drawings. These end pinions 35 and 36 of the shafts 30 and 31 respectively have the teeth thereof in meshing engagement with racks 37 and 38 respectively. The racks 37 and 38 are dove-tailed for vertical sliding in the brackets 32, and their upper ends are detachably connected as shown at 40 in Figures 2 and 3 of the drawings, to the corners of the top wall C, preferably at a marginally solid portion 16^a of the top wall C. The racks 37 are straight, and connected in right angled depending relation from the top wall C, and it is to be noted that there is a rack at each corner of the top wall C meshing with a pinion 35 or 36, as the case may be. Upon counter-rotation of the shafts 30 and 31 it 45 is apparent that the top wall C and the grids therewith will be elevated and lowered. This rotation of the shafts 30 and 31 is accomplished by providing a transverse operating shaft 45, shown in Figures 1 and 4 of the drawings, the ends of which bear in the intermediate brackets 32 of the shafts 30 and 31, the right end of the shaft 45 extending through the wall 12 of the stationary frame of the range and having a lever or 50 crank wheel 47 secured therewith to permit manual rotation of the shaft 45. The shaft 45 has keyed therewith worms 49 and 50, housed in the intermediate shaft housings 32 and respectively meshing with worm gears 51 and 52 keyed on the intermediate portions

of the shafts 30 and 31 respectively. The worms 49 and 50 are pitched in opposite directions, as are also the worm gears 51 and 52, so that upon rotation of the shaft 45 the shafts 30 and 31 will be rotated in opposite directions, to either feed all of the toothed racks 37 and 38 upwardly or downwardly, to accomplish the elevation or lowering of the entire top wall structure of the range with respect to the plurality of burners which cannot be elevated or lowered. 70 75

It is to be particularly noted that the racks 37 and 38 are so dove-tailed in their respective brackets 32 provided therefor, that they are held against tipping. The housings 32 have the tops thereof slotted merely to permit the racks 37 and 38 to slide therethrough. Otherwise the said housings of the brackets 32 cover the gear details therein against collection of foreign materials. 80 85

In the form of invention B, a pair of shafts 60 and 61 are rotatably supported at the inner sides of the walls 11 and 12 of the stationary structure of the range. Thus, the shaft 60 is supported at its ends by brackets 63 secured to the wall 11 at the inside thereof, as shown in Figures 5 and 6; an intermediate bracket 64 also being provided on the wall for said shaft. Similarly the shaft 61 is rotatably supported at its ends in bearing brackets 66 secured to the inside surface of the wall 12 and extending normal thereto. Furthermore, an intermediate bracket 67 is provided on the wall 12 for the shaft 61. 90 95

At the ends thereof the shafts 60 and 61 are each provided with radially extending arms 70, having pivotal connection at their free ends with links 72 which extend upwardly and are pivotally connected at 74 with brackets or bearings 75 secured to the undersurface of that portion of the top wall structure C which is laterally of the grids, as shown at 16^a. With this connection of the shafts 60 and 61 at their ends with the wall C it is apparent that upon rotation of the shafts 60 and 61, in the proper direction, the top wall C will be elevated and lowered with respect to the burners to accomplish the purposes of the invention above outlined. It is to be particularly noted that the end connection of linkage upon the shafts 60 and 61 insures that the top wall structure C will find an elevating and lowering connection at each corner thereof. 100 105 110 115

For the purpose of simultaneously moving the shafts 60 and 61 in the same direction, I prefer to provide an operating rod 80, extending transversely through the stove range below the burners thereof, which at its remote end is pivoted at 81 with an arm 82 keyed on the shaft 60. The arm 82 is radial on the shaft 60, as well as rigidly connected therewith, and it is disposed in a bell crank arrangement with the arms 70 of said shafts, above mentioned. The operating rod 80 at 120 125 130

its opposite end extends transversely through an opening provided in the wall 12 of the stove, as shown at 85 in Figure 8 of the drawings. This opening 85 permits the rod 80 to be elevated and lowered slightly adjacent the wall, so that any of a number of notches 87 provided along the lower edge of the rod may be notched in a detent flange 88 which is secured on the wall 12 at the opening 85, for the purpose of holding the rod 80 against accidental inward or outward movement, as would ordinarily cause an elevation or lowering of the top wall of the gas range. It is to be particularly noted that the operating rod 80 has an arm 89 pivoted therewith at 90; the arm 89 being radially of and rigid on the shaft 61 above mentioned. Since such an operating means necessitates that both the shafts 60 and 61 rotate in the same direction to enable the elevation and lowering of the top wall C, it is intended that the arms 70 of the shafts 60 and 61 lie parallel, or substantially parallel, and the connecting links 72 of both of said shafts are preferably also in parallelism.

From the position shown in Figure 6, upon moving the rod 80 inwardly upon disconnection of the notch 87 from the detent 88, it is to be noted that the arms 70 will be moved downwardly, and through the link connections 72 the top wall C of the range will be lowered to place the grids closer to the burners. The position of burners and grids, as shown in Figure 6, are in their maximum spaced relation, while the closest spaced relation of the same is designated in Figures 7 and 8 of the drawings.

While I realize that it has heretofore been proposed to vary the distance between burner and grid, so far as I am aware, no prior device shows an arrangement which enables elevation and lowering of the entire top wall of a range, together with its grids, relative to burners.

Various changes in the shape, size, and arrangement of parts may be made to the forms of invention herein shown and described, without departing from the spirit of the invention or the scope of the claims.

I claim:

1. In a gas range the combination of a stationary lower frame portion including burners connected therewith, a top wall structure including grids for the respective burners, and means connected with the lower frame portion of the range for operatively elevating and lowering the top wall and the grids therewith.

2. In a gas range the combination of a body frame having burners operatively associated therewith and a top wall removably associated therewith above the burners, grids carried by the top wall for the respective burners, and means operatively mounted upon the body frame for elevating and lowering the

entire top wall including the grids towards and away from the burners to place the grids at proper spaced distances with respect to the burners.

3. In a gas range a body frame having burners operatively associated therewith and a top wall movably associated with the body frame above the burners and including grids for each of the burners, detachable from the top wall, and means for elevating and lowering the top wall and the grids therewith for spacing the grids at desired distances with respect to the burners in relation to the fuel being used.

4. In a gas range a body frame having a burner operatively associated therewith, a top wall having a removable grid for supporting utensils above the burner, and means for elevating and lowering the top wall with respect to the body frame to properly space the grids from each burner.

5. In a gas range a body frame including opposite walls with burner means therebetween, a top wall including grid means for supporting utensils above the burner means, and means supported by said opposite walls for operatively lowering and elevating the top wall to properly space the grid means with respect to the burner means.

6. In a gas range a body frame having upstanding walls, a stop wall structure having a plurality of grids thereon, burner means operatively supported by the body frame, shafts rotatable upon said upstanding body frame walls, and means connecting said shafts and the top wall for elevating the latter or lowering it with respect to the burner means.

7. In a gas range structure a body frame having upstanding walls, burners carried by said body frame, a top wall structure including a frame and grids individually supported thereby for the respective burners, shafts rotatably supported by the opposite walls of said body frame, links operatively connecting said shafts eccentric thereto with the top wall, and means for simultaneously operating the shafts to elevate or lower the top wall.

8. In a gas range structure, a body frame having opposite walls, burners carried by said body frame, a top wall structure including a frame and grids individually supported thereby for the respective burners, cranks operatively supported by the said opposite walls, means for synchronously operating said cranks, and means connecting said cranks with the top wall for elevating and lowering the top wall together with the grids with respect to the burners upon operation of said cranks.

9. In a gas range structure a body frame having upstanding walls, burners carried by said body frame, a top wall structure including a frame and grids individually supported thereby for the respective burners, bell crank levers pivotally mounted upon said

body walls and between said body walls, a rigid rod pivotally connecting said bell crank levers at similar ends for simultaneous movement, means to adjustably hold said rod in predetermined positions and means movably and individually connecting the other ends of said bell crank levers with said top wall whereby upon movement of said connecting rod the top wall together with its grids will be elevated or lowered with respect to said burners.
